UNITED STATES PATENT OFFICE.

WILLIAM J. WHEELER, OF PATCHOGUE, NEW YORK.

TRIP RIDING-PAWL.

1,226,731.

Specification of Letters Patent. Patented May 22, 1917.

Application filed March 31, 1917. Serial No. 158,859.

To all whom it may concern:

Be it known that I, WILLIAM J. WHEELER, a citizen of the United States, residing at Patchogue, in the county of Suffolk and 5 State of New York, have invented new and useful Improvements in Trip Riding-Pawls, of which the following is a specification.

This invention relates to cable stoppers, and more particularly to the riding pawl 10 which is adapted to engage the links of the chain or cable to prevent paying out of the latter.

Cable stoppers of the type now generally employed on ships are provided with a one-piece pawl pivoted at one end and adapted to engage the links of the chain at its free end, and with this arrangement, when the anchor is "riding by the pawl," that is, prevented from running, due to the engagement 20 of the pawl against the links of the chain, it is necessary, to pay out the chain, to first put the windlass in operation and heave in the chain slightly, to relieve the pawl of the strain of the cable, and then swing the pawl 25 upwardly out of engagement with the chain. With my construction unnecessary delay in paying out the chain is obviated and this is of considerable advantage, as it is always desired to quickly release the chain to prevent 30 danger of the anchor dragging, especially in squally weather.

The present invention has as its main purpose to provide the chain stopper with an improved trip or pawl which will permit 35 of release of the chain without first relieving the strain thereof upon the pawl. My improved trip is very simple in construction, efficient in operation, and is strongly made so as to withstand the strain of the 40 chain and anchor thereupon.

The above and other objects of my invention are obtained in the structure described in the following specification and illustrated in the accompanying drawings 45 wherein,—

Figure 1 is a sectional view through a chain stopper showing my improved trip applied thereto.

Fig. 2 is a top plan view of the structure shown in Fig. 1.

Fig. 3 is a side elevational view of my improved trip, the same being shown in broken condition.

Fig. 4 is a top plan view of the trip.

55 Referring to the drawings, wherein like numerals represent like parts in the several

views, 10 designates the channel or pipe member of the chain stopper through which the chain or cable is adapted to pass. The channel member 10 is provided at each side 60 with a sleeve or pipe section 11 through which extends a horizontally disposed guide-bar or rod 12, the latter being fixed in suitable posts 13. The sleeves 11 are slidably mounted upon the guide rods 12 and are 65 normally urged in a direction toward the windlass by coiled springs 14 encircling the rods 12 and interposed between the sleeves and the posts 13. Extending transversely of and adjacent to the upper end of the 70 channel member 10 is a pivot post 15 to which my improved trip or pawl is pivoted. The springs 14 permit of a slight movement of the channel member 10 and are adapted to act as buffers which minimize 75 the shock or jar to which the chain and stopper would be otherwise subjected when the ship is riding at anchor.

The chain stopper above described is of a well-known type, and it is to be understood that the present invention is not limited to the particular kind of chain stopper illustrated, as this stopper is shown for illustrative purposes only.

My improved trip or pawl comprises two 85 parts, a first part 16 pivoted to the pivot post 15 and a second part 17 pivoted to the free end of the part 16. The part 17 has an extension 19 which fits in between a pair of ears 20 on the first part, and the extension 90 and ears are transversely apertured so that, when the parts are assembled, a through opening is obtained for the reception of a bolt 18. It will be noted from Figs. 1 and 3, that the parts 16 and 17 of the trip are 95 provided with opposed shoulders 21 which, when the trip is in extended position, are in engagement with each other, so that the trip cannot fold upwardly and backwardly upon itself. Preferably the trip tapers from its 100 upper end to its lower end, and the forward lower edge of the trip constitutes a nose 22 which engages against the links of the chain and clamps the same to prevent running thereof. The construction is such that, the 105 pivotal point on which the parts 16 and 17 of the trip are connected, that is, the center of the bolt 18, will move past the line of center through the pivotal post 15 and the nose 22 so that the tendency of the chain through 110 its pull against the trip, is to fold the parts of the trip upwardly to maintain the shoul-

ders 21 in engagement and hold the trip in extended position.

The portions 16 and 17 of the trip have on their upper surfaces upstanding apertured 5 ears or projections 23 and 24, respectively, and the apertures in these ears are in alinement with each other when the trip is in extended position, so that the same may receive a locking rod 25. The rod 25 adjacent 10 its forward end has a radially extending pin 26 adjusted to engage against the edge of the ear 23 so as to prevent the rod from being withdrawn from the ear 23. The rod is also provided with a second radial pin 27 15 which is adapted to slide through a longitudinal slot 28 extending from one edge of the ear 23 and terminating short of the front edge thereof in a circumferential or segmental slot 29. The latter slot 29 receives 20 the pin 27 when the rod is moved into its foremost position and then given a partial revolution.

The operation of my improved trip will be readily understood from the foregoing description. In the extended position shown 25 in Fig. 1, and in which position the nose 22 is engaging one of the links of the chain so as to prevent running thereof, the shoulders 21 on the parts of the trip abut each other and 30 the parts are held in this position by the pull of the chain due to the fact that the center of bolt 18 is beyond the line through the center of post 15 and nose 22. When the parts are in this position, to insure against accidental 35 breaking of the trip, the rod 25 is caused to extend through the apertures in both of the ears or projections 23 and 24. By engaging the pin 27 in the peripheral slot 29 accidental withdrawal of the rod is 40 prevented.

When it is desired to pay out the chain, the rod 25 is given a partial revolution so as to move the pin 27 in the slot 29 and bring the same in registry with the longitudinal 45 slot 28. The rod is then drawn outwardly until the forward end thereof is out of engagement with the aperture in the ear 24 and the pin 26 engages the forward edge of the ear 23. A downward force is now applied to the upper end of the rod 25 which causes the trip to pivot about the post 15. After the center of the bolt 18 is thus raised above the line running through the center of the post 15 and the nose 22, the pull of the 55 chain against the nose will break the trip at the bolt 18 and cause the part 17 to fold downwardly and backwardly upon the part 16. Due to the fact that the center of bolt 18 is only slightly out of alinement with the nose 22 and post 15, the distance which the rod 25 must be moved to break the trip is 60 slight, and thus a sharp downward jar or push will be sufficient to break the trip.

This invention is susceptible of various 65 changes and modifications which would be

within the spirit of my invention without departing from the scope of the following claims.

What I claim is:

1. A trip pawl for chain stoppers pivoted 70 at one end and adapted to engage a cable at its free end and comprising two parts hingedly connected, the line on which said parts are connected being beyond the line of center passing through the pivotal line of 75 the trip and the chain-engaging end thereof.

2. A trip pawl for chain stoppers pivoted at one end and adapted to engage a cable at its free end, and comprising two parts hingedly connected, and means for locking 80 said parts in extended or alined position.

3. A trip pawl for chain stoppers pivoted at one end and adapted to engage a cable at its free end and comprising two parts hingedly connected, an apertured member 85 on each of said parts, and a rod extending through the apertures of said members to lock said parts in extended or alined position.

4. A trip pawl for chain stoppers pivoted 90 at one end and adapted to engage a cable at its free end and comprising two parts hingedly connected, the line on which said parts are connected being beyond the line passing through the pivotal line of said trip 95 and the chain engaging end thereof when the parts are in extended or alined position, an apertured member on each of said parts, and a rod adapted to extend through the apertures of said members to lock the parts 100 in extended or alined position.

5. A trip pawl for chain stoppers comprising two parts hingedly connected together, ears on each of said parts, openings in said ears which are in alinement when 105 the parts are in extended position, and a rod adapted to extend through said openings to lock the parts in extended position.

6. A trip for chain stoppers pivoted at 110 one end and adapted to engage a cable at its other end and comprising two parts hingedly connected together, ears on said members having openings which are in alinement when the parts are in extended position, a rod adapted to extend through said 115 openings to lock the parts in extended position, and means for preventing withdrawal of the rod from said ears.

7. A trip pawl for chain stoppers pivoted at one end and adapted to engage a cable at 120 its other end and comprising two parts hingedly connected together, ears on said parts having openings which are in alinement when the parts are extended, a rod in 125 said openings for locking said parts in extended position, and means on the rod for maintaining the rod in locking position.

8. A trip pawl for chain stoppers comprising two parts hingedly connected together, ears on said parts having openings 130

- which are in alinement when the parts are in extended position, a rod adapted to extend through said openings to lock the parts in extended position, and a pin on said rod, 5 one of said ears having a longitudinal slot terminating in a peripheral slot and the latter slot being adapted to receive said pin to maintain the rod in locking position.
9. A trip pawl for chain stoppers comprising a pivoted first part, a second part 10 hingedly connected to said first part, an ear on each of said parts, openings in said ears which are in alinement when the parts are in extended position, said ear of the first 15 part having a longitudinal slot terminating in a peripheral slot, a rod adapted to engage in the alined openings of said ears to lock the parts in extended position, and a pin on said rod adapted to move through said longitudinal slot and engage in said peripheral slot 20 to prevent withdrawal of the slot from locking position, and a pin on said rod between said ears.
10. A trip pawl for chain stoppers comprising a pivoted first part, a second part hingedly connected to said first part, an ear 25 on each of said parts, openings in said ears which are in alinement when the parts are in extended position, said ear of the first part having a longitudinal slot terminating in a peripheral slot, a rod adapted to engage 30 in the alined openings of said ears to lock the parts in extended position, a pin on said rod adapted to move through said longitudinal slot and engage in said peripheral slot 35 to prevent withdrawal of the slot from locking position, and a pin on said rod between said ears.

In testimony whereof I have hereunto set my hand in presence of two subscribing witnesses.

WILLIAM J. WHEELER.
